ATTORNEY.

UNITED STATES PATENT OFFICE.

CHARLES C. WOODBERRY, OF CINCINNATI, OHIO.

DESIGN FOR AN AUTOMOBILE-RADIATOR CURTAIN-HOOD.

59,398.

Specification for Design.

Patented Oct. 11, 1921.

Application filed May 9, 1921. Serial No. 468,177. Term of patent 7 years.

To all whom it may concern:

Be it known that I, CHARLES C. WOODBERRY, a citizen of the United States of America, and a resident of the city of Cincinnati, in the county of Hamilton and State of Ohio, have invented a new, original, and ornamental Design for an Automobile-Radiator Curtain-Hood, of which the following is a specification, reference being had to the accompanying drawing, forming part thereof.

In the drawing:

Figure 1, is a front isometric view of an automobile radiator curtain hood, showing my new design, and

Fig. 2, is a view looking down upon the top thereof.

I claim:

The ornamental design for an automobile radiator curtain hood, as shown.

Witness my hand at the city of Cincinnati, in the county of Hamilton and State of Ohio, this 6th day of May, 1921.

CHARLES C. WOODBERRY.
